UNITED STATES PATENT OFFICE.

CHESTER E. TRAVIS, OF MOROCCO, INDIANA.

EXPLOSIVE-ENGINE.

1,202,613.

Specification of Letters Patent. Patented Oct. 24, 1916.

Application filed August 31, 1915. Serial No. 48,244.

To all whom it may concern:

Be it known that I, CHESTER E. TRAVIS, a citizen of the United States, residing at Morocco, in the county of Newton, State of Indiana, have invented certain new and useful Improvements in Explosive-Engines; and I do hereby declare the following to be a full, clear, and exact description of the invention, such as will enable others skilled in the art to which it appertains to make and use the same.

This invention relates to explosive engines.

The object of the invention is to provide an explosive engine of the double action type or wherein an explosion takes place at each end of the cylinder in proper sequence, and to further provide improved means for governing the speed of the engine.

A further object of the invention is to provide an explosive engine which will be comparatively simple in construction and reliable in use.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a plan view of an explosive engine constructed in accordance with the invention; Fig. 2, a side elevation of same; Fig. 3, a section on the line 3—3 of Fig. 1; Fig. 4, a rear view of the engine; Fig. 5, a section on the line 5—5 of Fig. 3; Fig. 6, a section on the line 6—6 of Fig. 2; Fig. 7, a section on the line 7—7 of Fig. 1; and Fig. 8, an enlarged side elevation of a fragment of the engine with the parts in the position they would occupy when the engine is running at an excessive speed.

Referring to the drawings the invention is shown as comprising a base 10 upon which is mounted a cylinder 11. Slidably mounted in the cylinder 11 is a piston 12 to which is connected a piston rod 13 slidably in a suitable bearing 14 mounted in one end of the cylinder. The ends of the cylinder 11 are formed respectively of hollow castings 15 and 16 which are partitioned to provide intake and exhaust chambers 17 and 18 respectively. Communication between the cham-

ber 18 of the casting 15 with the interior of the cylinder 11 is controlled by an exhaust valve 19 normally held seated by a spring 20. Communication between the chamber 17 of the casting 15 with the interior of the cylinder 11 is controlled by an intake valve 21 normally held seated by a spring 22. Likewise communication between the chamber 18 of the casting 16 and the interior of the cylinder 11 is controlled by an exhaust valve 23, said valve being normally held seated by a spring 24. Communication between the chamber 17 of the casting 16 and the interior of the cylinder 11 is controlled by an intake valve 25 normally seated by a spring 26. The interior of the chamber 18 of the casting 15 communicates with an exhaust manifold 27, while the interior of the chamber 18 of the casting 16 communicates with an exhaust manifold 28. Likewise the interior of the chamber 17 of the casting 15 communicates with an intake manifold 29 while the interior of the chamber 17 of the casting 16 communicates with an intake 30 manifold 30.

Mounted upon the cylinder 11 and operatively disposed with respect to the combustion ends of said cylinder are spark plugs 31 and 32 respectively through the medium 35 of which the charge at each end of the cylinder is exploded at the proper time.

Mounted upon the base 10 and secured to the casting 15 is a cross head guide 33 in which is slidably mounted a cross head 34 connected to the piston rod 13. Pivoted to this cross head 34 is a pitman 35 which latter is in turn operatively connected to a crank shaft 36 rotatably mounted in bearings 37 secured to the base 10. Fixed on the crank shaft 37 are the usual fly wheels 38. Mounted upon the base 10 is a bearing 39 in which is rotatably mounted a cam shaft 40 carrying cams 41 and 42. Fixed on the shaft 40 is a gear 43 which meshes with a gear 44 fixed upon the crank shaft 36. Also fixed upon the crank shaft 36 is a belt wheel 45 the purpose of which will presently appear. The crank shaft 36 carries a timer 47 which includes the usual make and break elements 48 which rotates with the shaft 36.

Mounted upon the guide 33 is a bracket 49 which operatively supports a governor 50. This governor includes the usual vertical shaft 51 and member 52 slidably on said shaft. Rotatably mounted in the bracket 49 is a shaft 53 which has fixed thereon a bev-

2ed gear 54 meshing with a beveled gear 55 fixed on the shaft 51. Also fixed on the shaft 53 is a belt wheel 56 disposed in line with the belt wheel 45. Traveling on the 5 belt wheels 45 and 56 is a belt 57 whereby the rotation of the crank shaft 36 is imparted to the shaft 53 and governor 50. Pivotaly mounted upon the bracket 49 is an arm 58 one end of which is pivotaly connected to the member 52 of the governor, while the other end of said arm pivotaly supports a member 59. Depending from this member 59 are rods 60 and 61 the purpose of which will presently appear. Mounted 10 upon the base 10 are guides 62 in which is slidably mounted a tappet rod 63. One end of this rod 63 carries a roller 64 adapted to be engaged by the cam 41 during the rotation of the shaft 40. Mounted on the casting 15 16 is a bracket 65 in which is pivoted a lever 66 having one end pivotaly connected to the rod 63 while the other end thereof is operatively engaged with the stem of the valve 23.

20 Mounted upon one of the guides 62 and also connected to the guide 33 is a guide 67 in which is slidably mounted a tappet rod 68 one end of which carries a roller 69 adapted to coöperate with the cam 42 during the rotation of the shaft 40. Pivoted upon one of the guides 62 is a lever 70 one end of which is pivotaly connected to the rod 60 while the other end thereof is adapted to engage a projection 71 on the rod 63 under certain 25 conditions to prevent movement of the rod 63 longitudinally under the influence of the spring 24. Likewise there is pivoted on the guide 67 a lever 72 one end of which is pivotaly connected to the lower end of the rod 61 while the other end of said lever is adapted to engage a projection 73 on the rod 68 under certain conditions to prevent movement of the rod 68 longitudinally under the influence of the spring 22. The rod 63 carries 30 a contact 74 adapted to be engaged by a contact rod 75 mounted on one of the guides 62 and insulated therefrom. Likewise the rod 68 carries a contact 76 adapted to be engaged by a contact rod 77 mounted 35 on the guide 67 and insulated from the latter. The contact 74 and contact rod 75 and likewise the contact 76 and contact rod 77 are included in the ignition circuit of the engine so that when said contacts and contact rods are out of engagement the circuit 40

45

50

55

through respective spark plugs will be broken.

In the operation of the engine under normal conditions the cams 41 and 42 coöperating with the tappet rods 63 and 68 respectively properly control the intake and exhaust of the engine, it being of course understood that the intake valves 19 and 25 are opened under the influence of the suction created by the piston 12. The ignition of the charge at either end of the cylinder 11 is effected by the timer 47. When the speed of the engine increases beyond a predetermined extent the member 52 of the governor will move downwardly and rock the lever 58. This action will cause the rods 60 and 61 to move upwardly and rock the levers 70 and 72 to dispose the free ends of the latter in the path of respective projections 71 and 73 and thus lock the exhaust valves of the engine in open position and also hold the contact rods 75 and 77 out of engagement with respective contacts 74 and 76 and thus break the ignition circuit of the engine. As soon as the speed of the engine is decreased to the desired extent the member 52 of the governor will move upwardly and rock the levers 70 and 72 out of engagement with respective projections 71 and 73 when the operation of the engine will again become normal.

What is claimed is:—

In an explosive engine, the combination of a cylinder, an exhaust valve, means normally holding the exhaust valve in closed position, a slideable tappet rod adapted during its reciprocation to open the exhaust valve intermittently, a projection on said rod, a governor, a pivoted lever having one end directly connected to the governor, a pivoted locking lever, and connections between the locking lever and the first lever whereby the locking lever will operate when the speed of the engine increases a predetermined extent to move the lever into engagement with said projection and lock the tappet rod in position to hold the exhaust valve open.

In testimony whereof, I affix my signature, in the presence of two witnesses.

CHESTER E. TRAVIS.
